SHOE

Laurence M. Oakley, Trenton, N. J., assignor to
Essex Rubber Company, Trenton, N. J., a corporation of New Jersey

Application June 4, 1938, Serial No. 211,717

2 Claims. (Cl. 36—2.5)

This invention relates to shoes. It is an object of the invention to provide an improved heel construction.

Other objects and advantages of the invention will appear hereinafter.

A preferred embodiment of the invention selected for purposes of illustration is shown in the accompanying drawing, in which,

Figure 1 is a side elevation of a shoe embodying my invention.

Figure 2 is a top plan view of a heel wedge.

Figure 3 is a central longitudinal cross-sectional view of the same.

Referring to the drawing, the shoe comprises an upper 1, to which is secured a welt 2, which as illustrated is preferably extended rearwardly throughout the length of the shoe from toe to heel.

An outsole 3 likewise extends throughout the length of the shoe from toe to heel, and the front part of the said outsole may be secured to the welt in any suitable manner, as by stitching 4.

The rear part of said outsole is spaced from the rearward extension of the welt by a wedge 5 having a relatively flat portion 6 supporting the heel of the wearer, and a downwardly tapering portion 7 extending forwardly under the arch of the foot.

The outer wall or face of said wedge is grooved or concaved as illustrated at 8 to provide upper and lower horizontal flanges 9 and 10. This grooved shape has several advantages. First, it is attractive in appearance, since it gives the impression of lightness and the curved shape is in itself pleasing. Second, if the wedge is made of rubber, as is preferable, the grooving of the outer wall adds to the resilience or springiness

of the heel. Third, the flanges 9 and 10 provide means by which the welt and outsole, respectively, may be stitched to the wedge. In some forms of shoes or sandals it may be sufficient to secure these parts together merely by cementing them together, but where stitching is desired the said flanges are additionally useful for this purpose.

Preferably the wedge is also provided with a recess 11 which reduces the weight of the wedge 10 and at the same time increases its springiness.

It will be understood that the invention may be variously modified and embodied within the scope of the subjoined claims.

I claim as my invention:

1. A shoe comprising a welt extending throughout the length of the shoe from toe to heel, an outsole also extending throughout the length of the shoe from toe to heel, and a molded rubber heel wedge interposed between said welt and outsole, said wedge having a deeply grooved outer wall provided with upper and lower horizontal flanges for attachment to said welt and outsole, respectively.

2. A shoe comprising a welt extending throughout the length of the shoe from toe to heel, an outsole also extending throughout the length of the shoe from toe to heel, a molded rubber heel wedge interposed between said welt and outsole, said wedge having a deeply grooved outer wall provided with upper and lower horizontal flanges for attachment to said welt and outsole, respectively, a line of stitching securing said upper flange to said welt, and a line of stitching securing said lower flange to said outsole.

LAURENCE M. OAKLEY.
